ALEXANDER T. KASLEY, OF MOORE, PENNSYLVANIA, ASSIGNOR TO WESTINGHOUSE ELECTRIC & MANUFACTURING COMPANY, A CORPORATION OF PENNSYLVANIA.

INTERNAL-COMBUSTION-ENGINE CYLINDER.

Application filed January 4, 1927. Serial No. 158,969.

This invention relates to internal combustion engines, more particularly to internal combustion engines of the opposed piston Diesel type, and has for its object the provision of an improved cylinder construction for such engines, which shall be simple of design, of relatively light weight for the power developed within the cylinder, which shall incorporate simple improved means of cooling, and which shall have the requisite strength to withstand the stresses to which it is subjected.

Apparatus embodying features of my invention is illustrated in the accompanying drawing wherein:

Fig. 1 is a longitudinal sectional view of a cylinder made in accordance with my invention; and,

Fig. 2 is a sectional view taken along the line II—II of Fig. 1.

Referring to the drawings, I show my improved cylinder, indicated generally, at 10, having therein a pair of opposed pistons 11 and 12. Fuel is admitted to the cylinder by means of any suitable mechanism through openings 13. After combustion of the fuel in the cylinder the gases of combustion are exhausted through openings 14 into an exhaust manifold 16.

Scavenging air for sweeping out the products of combustion and for supplying air for the combustion of a subsequent charge of the fuel is admitted to the cylinder through suitable scavenging ports 17 from a scavenging air manifold 18. The fuel inlet openings 13, the exhaust openings 14 and the scavenging openings 17 may be said to be radially-extending, that is, they extend in such a direction as to pass through the wall of the cylinder between its exterior surface and its interior bore.

The walls of the cylinder surrounding the central bore wherein the pistons 11 and 12 are located are relatively thin in cross section except in areas adjacent to the inlet ports 13, the exhaust ports 14, and the scavenging ports 17. In the areas surrounding these ports the walls are made relatively thick as shown at 21, 22 and 23. The thickened wall surrounding the fuel inlets 13 gives sufficient strength to the walls in the areas wherein the highest pressures occur from the freshly ignited fuel. The thickened walls at 22 and 23, adjacent the exhaust ports and scavenging ports respectively,

gives the requisite strength to the cylinder in that area which would otherwise be weakened on account of the relatively large openings defining the exhaust ports and scavenging ports. The remainder of the cylinder wall, as may be seen from the drawing is relatively thin, just sufficient to withstand the stresses due to pressure in the cylinder with safety. The cylinder is provided with thickened portions 22^a and 23^a spaced outwardly from the thickened portions 22 and 23, respectively, for purposes to be described.

Surrounding the thinner portion of the walls of the cylinder are a plurality of jacket members or sleeves 26, 27, 28 and 29. The members or sleeves 26, 27, 28 and 29 are arranged to bridge the spaces between adjacent thickened portions of the cylinder and to provide, with respect to the relatively thin portions of the cylinder, water jacket spaces 26^a, 27^a, 28^a and 29^a, respectively. The water jacket spaces 26^a, 27^a, 28^a and 29^a communicate with each other by means of cooling passages 31, 32 and 33 formed in the thickened wall portions 23, 21 and 22, respectively. The passages 31, 32 and 33 may be formed by removing or omitting material from the thickened wall portions 21, 22 and 23 in between the cylinder openings. This may be done, for example, by drilling holes in the locations illustrated in the drawing. Cooling water is admitted at one end of the cylinder through a conduit 34, which communicates with the circumferential space 34^a provided in the thickened portion 23^a, the circumferential space communicating, by way of passageway means 34^b, with the jacket space 26^a. Cooling water passes from the jacket space 26^a through the passages 31 to the space 27^a; from the jacket space 27^a water passes through the passages 32 to the space 28^a; from the space 28^a water passes through the passages 33 to the jacket space 29^a; and from the latter space water is discharged through the conduit 36. Sufficient cooling passages to insure against overheating of the thickened wall portions are distributed entirely around the cylinder as shown for the passages 32 in Fig. 2, which may be taken as representative of the arrangement of the passages in the thickened wall portions 22 and 23.

It will be noted that the thickened portions 23^a, 23, 21, 22 and 22^a are of such relative radial thicknesses that the sleeve or

jacket members 26, 27, 28 and 29 may be readily slipped on endwise over the cylinder ends and then secured to the thickened portions in any suitable manner, as by welding, 5 soldering and the like. The thickened portion 23 is provided with a part 23^b at the inner side of the opening 17 which is of slightly greater radial thickness than the remainder of such thickened portion 23, the 10 part 23^b being of substantially the same radial thickness as the portion 21 in order that a sleeve member 27 of substantially uniform diameter may be secured in place with respect to the thickened portions 23 and 21 and 15 bridge the space therebetween. As shown in Fig. 1 the thickened portion 23^a is of slightly less radial thickness than the major part of the thickened portion 23; and, in order that the sleeve 26 may fit the thickened 20 portion 23 closely and present, with respect to the latter, a smooth exterior flush surface, I show a rabbeted connection 26^b with respect to the thickened portion 23. The thickened portions 22 and 22^a are of substantially 25 the same radius and slightly less than that of the thickened portion 21. The sleeve 28 fits the thickened portion 21 and is slightly constricted to fit the thickened portion 22. The sleeve 29 has terminal constricted 30 portions for fitting the thickened portions 22 and 22^a. The sleeve members fit the thickened portions and terminate short of the openings 13, 14 and 17, whereby parts of the thickened portions having such openings 35 are exposed for apparatus which is co-operative with such openings. Hence, it will be seen that the sleeve members 26 and 27 may be readily slipped on from the left-hand end of the cylinder and secured in place with respect to the thickened portions 40 in any suitable manner. Likewise, the sleeve members 28 and 29 may be slipped on from the right-hand end of the cylinder and secured in place. So far as my invention is 45 concerned, it is to be understood that any suitable radial thicknesses of the thickened portions may be provided so long as the sleeve members may be assembled and secured in place.

50 Referring particularly to Fig. 2, it will be seen that the cylinder 10 is supported and restrained against longitudinal movement at its mid portion by a pair of bracket members 41 and 42 secured to longitudinally-extending plate members 43 and 44. The bracket members 41 and 42 are secured to the cylinder 10 by means of plugs 46 and 47 which are screwed into the cylinder 10 and secured to the brackets 41 and 42 by means 55 of pins 48 and 49. The ends of the cylinder 10, shown at 51 and 52, are slidingly supported in ring members 53 and 54 so that the cylinder is free to expand and contract, away from its central restraining means, due 60 to temperature changes.

In a cylinder such as I have shown, it will be seen that the working forces of the engine are not imposed upon the cylinder due to the opposed piston type of construction. Furthermore, the supporting means I employ insures that the only stresses to which the cylinder is subjected are those due to pressure within the cylinder and to friction between the piston and cylinder. It will thus be seen that my improved structure 70 is such as to provide a cylinder with the least possible weight per unit of power developed and at the same time has adequate means for cooling it.

While I have shown my invention in one 80 form, it will be obvious to those skilled in the art that it is not so limited, but is susceptible of various other changes and modifications, without departing from the spirit thereof, and I desire, therefore, that only 85 such limitations shall be placed thereupon as are imposed by the prior art or as are specifically set forth in the appended claims.

What I claim is:

1. A cylinder for an opposed piston type 90 internal combustion engine having centrally disposed fuel inlet means, exhaust outlet means spaced from the fuel inlet means toward one end of the cylinder, and air scavenging inlet means spaced from the fuel inlet 95 means toward the opposite end of the cylinder from the exhaust outlet means, comprising a body portion having relatively thin walls the major portion of its length and thickened in areas adjacent to the fuel inlet 100 means, the exhaust outlet means and the scavenging inlet means, water jacket means surrounding the thinner wall portions of the cylinder, water inlet and outlet means provided at opposite ends respectively of the 105 cylinder, and means provided in the thickened wall portions for circulating water from the water inlet means to the water outlet means.

2. A cylinder for an internal combustion 110 engine of the opposed piston type comprising a one-piece body having a central bore and provided with centrally disposed fuel inlet means, said central portion of the cylinder defining a combustion space, said cylinder body having relatively thin walls the greater portion of its length but having its walls thickened at the central portion thereof, water jacket means surrounding the thin wall portions of the cylinder, water inlet 115 means communicating with the water jacket means at one end of the cylinder, water outlet means provided in the water jacket means at the other end of the cylinder, said thickened wall portions of the cylinder having 120 passages provided therein for the circulation 125 of cooling water from one end of the cylinder to the other.

3. In an internal combustion engine of the opposed-piston type, the combination of 130

- a one-piece cylinder having relatively thin wall portions for the major part of its length and having a central thickened wall portion provided with one or more radially-extending fuel admission openings and transverse cooling medium passages, jacket means cooperating with the thickened wall portion and with portions of the cylinder spaced from the thickened wall portion to provide jacket spaces at either side of the thickened wall portion, and means providing for the circulation of cooling medium through said jacket spaces and passages.
4. In an internal combustion engine of the opposed-piston type, the combination of a one-piece cylinder having relatively thin wall portions for the major part of its length and having a central thickened wall portion provided with one or more radially-extending fuel admission openings and transverse cooling medium passages, and having thickened wall portions disposed at either side of and spaced from the central thickened wall portion and provided with radially-extending openings and transverse cooling medium passages; sleeve means cooperating with the thickened wall portions to provide jacket spaces; and means providing for the circulation of cooling medium through the jacket spaces and passages.
5. In an internal combustion engine of the opposed-piston type, the combination of a one-piece cylinder having relatively thin wall portions for the major part of its length and having a central thickened wall portion provided with one or more radially-extending fuel admission openings and transverse cooling medium passages, and having pairs of spaced inner and outer thickened wall portions disposed at either side of and spaced from the central thickened wall portion, the inner thickened wall portions of said pairs being provided with radially-extending inlet and exhaust openings, respectively, and each having transverse cooling medium passages; sleeve means cooperating with the thickened wall portions to provide jacket spaces between adjacent thickened wall portions; and means providing for the circulation of cooling medium through the jacket spaces and passages.
6. In an internal combustion engine of the opposed-piston type, the combination of a one-piece cylinder having relatively thin wall portions for the major part of its length and having a central thickened wall portion provided with one or more radial fuel admission openings and transverse cooling medium passages, and having thickened wall portions disposed at either side of and spaced from the central thickened wall portion and provided with radially-extending openings and transverse cooling medium passages; sleeves bridging the spaces between adjacent thickened wall portions to provide jacket spaces, one sleeve having its ends arranged between the radially-extending inlet openings and the radially-extending fuel admission openings and the other sleeve having its ends arranged between the latter openings and the exhaust openings; and means providing for the circulation of cooling medium through the jacket spaces and transverse passages.
7. In an internal combustion engine of the opposed-piston type, the combination of a one-piece cylinder body having relatively thin wall portions for the major portion of its length, a plurality of circumferentially spaced inlet openings provided in the cylinder, a plurality of circumferentially spaced outlet openings provided in the cylinder, said inlet and outlet openings being spaced longitudinally from each other, thickened wall portions formed unitary with the cylinder and surrounding each of said openings, jacket means cooperating with the thickened wall portions and with portions of the cylinder spaced from the thickened wall portions to provide jacket spaces at either side of the thickened wall portions, said thickened wall portions being so formed as to provide passage-ways affording communication between the jacket spaces, and means providing for the circulation of cooling medium through the jacket spaces and passage-ways.
8. In an internal combustion engine of the opposed-piston type, the combination of a one-piece cylinder body having relatively thin wall portions for the major portion of its length, jacket flanges formed upon each end portion of the cylinder, fuel admission means provided in the cylinder between the jacket flanges, a plurality of circumferentially spaced scavenging fluid inlet openings provided in the cylinder between one of the jacket flanges and the fuel admission means, a plurality of circumferentially spaced exhaust openings provided in the cylinder between the other jacket flange and the fuel admission means, thickened wall portions formed unitary with the cylinder and surrounding each of said openings, jacket means cooperating with the jacket flanges and with the thickened wall portions to provide cylinder jacket spaces, said thickened wall portions being so formed as to provide passage-ways affording communication between the jacket spaces, and means providing for the circulation of cooling medium through the jacket spaces and passage-ways.
9. In an internal combustion engine of the opposed-piston type, the combination of a one-piece cylinder body having relatively thin wall portions for the major portion of its length and provided with centrally disposed, circumferentially spaced fuel admission openings, thickened wall portions formed unitary with the cylinder and surrounding each of said fuel admission open-

ings, jacket means cooperating with the thickened wall portions and with portions of the cylinder spaced from the thickened wall portions to provide jacket spaces at either 5 side of the thickened wall portions, said thickened wall portions being so formed as to provide passage-ways affording communication between the jacket spaces, and means providing for the circulation of cooling medium through said jacket spaces and said 10 passage-ways.

10. In an internal combustion engine of the opposed-piston type, the combination of a one-piece cylinder body having relatively 15 thin wall portions for the major part of its length, said cylinder being provided with centrally disposed, circumferentially spaced fuel admission openings, with circumferentially spaced scavenging fluid inlet openings 20 located on one side of the fuel admission openings and spaced longitudinally there-

from and with circumferentially spaced exhaust openings located on the other side of the fuel admission openings and spaced longitudinally therefrom, thickened wall portions formed unitary with the cylinder and surrounding each of said openings, jacket means cooperating with the thickened wall portions to provide cylinder jacket spaces 25 between the scavenging fluid inlet openings and the fuel admission openings and between the fuel admission openings and the exhaust openings, said thickened wall portions being so formed as to provide passage-ways affording communication between the jacket 30 spaces, and means providing for the circulation of cooling medium through the jacket spaces and passage-ways.

In testimony whereof, I have hereunto subscribed my name this 30th day of December, 1926.

ALEXANDER T. KASLEY.
